US00D823307S

(12) **United States Design Patent** (10) Patent No.: **US D823,307 S**
Zhang et al. (45) Date of Patent: ** Jul. 17, 2018

(54) **SCANNER**

(71) Applicant: **Hand Held Products, Inc.**, Fort Mill, SC (US)

(72) Inventors: **Pengfei Zhang**, Shanghai (CN); **Dezhi Yang**, Shanghai (CN)

(73) Assignee: **Hand Held Products, Inc.**, Fort Mill, SC (US)

(**) Term: **15 Years**

(21) Appl. No.: **29/624,749**

(22) Filed: **Nov. 3, 2017**

Related U.S. Application Data

(63) Continuation of application No. 29/555,990, filed on Feb. 26, 2016, now Pat. No. Des. 802,593.

(30) **Foreign Application Priority Data**

Aug. 28, 2015 (CN) 2015 3 0329152

CLAIM

The ornamental design for a scanner, as shown and described.

DESCRIPTION

FIG. 1 is a top plan view of a scanner in accordance with the present design;

FIG. 2 is a bottom plan view thereof;

FIG. 3 is a left side elevation view thereof;

FIG. 4 is a right side elevation view thereof;

FIG. 5 is a rear elevation view thereof;

FIG. 6 is a front elevation view thereof; and,

FIG. 7 is a front perspective view thereof.

The broken lines depict unclaimed features of the scanner and form no part of the claimed design.

1 Claim, 7 Drawing Sheets
